UNITED STATES PATENT OFFICE

BURPEE D. GREENLAW, OF FITCHBURG, MASSACHUSETTS, ASSIGNOR TO THE BROWN BAG FILLING MACHINE COMPANY, OF FITCHBURG, MASSACHUSETTS, A CORPORATION OF MASSACHUSETTS

COUNTER AND EJECTOR FOR PACKAGING MACHINES

Application filed May 14, 1931. Serial No. 537,467.

The invention relates to packaging machines and particularly to such machines adapted for packaging of nails, screws and the like. In such machines the most practicable feed and counting arrangements have included inclined chutes or slots across which the heads of the nails, screws, or other objects lie, while the shanks of the articles hang pendant through the slot. In the count and packaging means, there is usually a means to stop the whole body of articles or stock in the slot near the discharge end, and at a distance further from the point of discharge a second stop means operable so that when the first is in cleared position, the second holds the remainder of the stock while that portion (called the charge) between the stops moves from the chute. In the use of many prior machines the number of operations was limited by the time required for gravity to overcome the inertia of the charge and move it the required distance into the package. It has been attempted to reduce this time factor by forming multiple chutes in which a comparatively few articles are released from each of a number of slots simultaneously. But this multiplies the cost, size, weight, and complexity of mechanism and involves a new increment of delay in the need for greater distance and time in bringing to a central discharge point all of the articles from the numerous chutes. Means also has been provided to eject the charge positively (one being shown in the patent to Barter, 1,164,975) and it is a purpose of this invention to present an improved means to this end.

It is a further aim to present a novel form of clearer or ejector device for use in such machines.

Additional objects, advantages and features of invention reside in the construction, arrangement and combination of parts involved in the embodiment of the invention, as will be more readily understood from the following description and accompanying drawings, wherein

Figure 1 is a top view of a chute, charge forming and discharge mechanism embodying my invention, with parts broken away.

Figure 2 is a similar view with the parts shown at discharge position.

Figure 3 is a horizontal section of the carriage in initial position.

Figure 4 is an elevation from the right of Figure 1.

Figure 5 is a similar view from the left of Figure 1.

Figure 6 is a cross section of the mechanism.

Figure 7 is a fragmentary elevation of the mounting and operating connection of the arm 59, as viewed from the right of Figure 4.

Figure 8 is a formal showing of the cam drive for the arm 63, the arm being broken away before the cam.

Reference is made to the patents to Cummings, 539,171, May 14, 1885 and to Barter, 1,164,975, for familiar details of construction and to such machines as now in use.

There is illustrated a part of a nail counting and packaging machine including a nail chute 11, by which they are fed to the counting and packaging mechanism. The packaging mechanism may include any construction suitable for holding a container to receive the nails to be packaged.

A funnel moves into position in the receptacle when the charge is to be introduced into the receptacle, as in Cummings or Barter.

This machine also includes a main driving shaft substantially as in the patent to Cummings, upon which a gang of cams, cranks and pulleys or sprockets are mounted as required for peculiar functions involved in adapting the machine to various uses.

The nail chute 11 may be of such form as to adapt the machine to particular articles, several such forms being known. In the present instance it comprises two rails 14 with opposed flanges 15, the rails being fixed sufficiently spaced apart to afford a slot 16 between the flanges 15 of sufficient width to receive loosely the pendant shanks of the nails 17 to be packaged, while the heads of the nails rest upon the respective rails slidably. There has been disclosed in the above patent to Barter (Figures 5 to 8), a count device consisting of alternately oper-

ated detents numbered in the patent 58 and 68 operated by a cam arm having parts numbered in that patent 64 and 73, which arm may be utilized here. The prior lower 5 detent is replaced here by a gate 20, which is raised instead of sliding back to open the chute.

The upper detent or stop 19 consists of a bearing 21, in which a rock shaft 22 is mounted. The shaft projects over the slot 16 and carries a finger spring 23 having a lower end 10 toward the discharge end of the chute adapted to bear upon the chute across the slot, and being longitudinally adjustable so that its stop end may be adjusted as required. This 15 adjustment 23' may be utilized to vary the number of nails in the charge, with other adjustments. On the outer or left hand end of the shaft 22 there is a wiper arm 24, 20 carrying a wiper roller 25, bearing upon the oscillating cam segment 18 corresponding to the cam 63—64 of Barter patent mentioned, mounted on an arm by which it is operated to be projected forwardly to an extreme position 25 and immediately retracted once for every filling operation, with an interval of rest at its rearmost position. This cam is formed with a low portion 27 extending over its major forward part, and a high part 28 at its 30 rearmost part. The roller 25 bears constantly on this cam by action of the spring 29, and the arm 24 is directed rearwardly, so that with the finger 23 in raised position when the roller engages the low part of the cam, forward movement of the cam and engagement of the high part with the roller will move the finger 23 to closed position, preventing movement of nails from that point down 35 the slot while the charge is ejected.

40 It is after this closing movement of the finger 23 but while it remains closed that the gate 20 operates as will be explained.

The gate 20 (Figures 1, 2 and 6) consists of a gate shaft 30 mounted on the outer side 45 of the left hand rail of the chute to rock on an axis parallel to the chute. The mounting of the shaft may comprise ears 31 projected from a mounting block 32 fixed beside the chute. The shaft has secured thereon a plate 33, which in closed position of the gate lies 50 closely over the upper side of the block 32. The top of the plate 33 in this position lies in approximately the same plane with the tops of the chute rails 14, and on the top of the plate there is adjustable the gate finger 36, which extends sufficiently to lie across the slot 16 close upon or over the top surfaces of the rails. The finger 36 has a base portion 37 55 at right angles thereto formed with a longitudinal slot through which there is engaged a clamp screw 38 engaged in one of a longitudinal series of threaded holes 39 in the plate 33. The slot and the holes enable the finger to be adjusted at any desired distance 60 below the stop 19, so as to regulate the count.

The form and time of movement of the cam 18 are such that the gate is in closed position before the upper or first stop is lowered to the slot 16, and is opened after a short interval before the upper stop is again raised. 70

The shaft 30 is provided with a downwardly extended arm 40 engaged by a spring 35, tending to move the arm and the gate piece to closed position, where the spring holds the gate except during the short interval of discharge of the charge, as will be described. The arm 40 is close beside the cam 18 and on the latter a lateral inclined cam piece 41 is 75 adjustably mounted which, when the cam 18 is near the extreme forward position engages the arm 40 and operates the gate, opening it only during the terminal forward movement and initial rearward movement of the cam 18, the arm being of a width for the cam part 41 to remain in engagement with the left side 80 thereof holding the gate open during these movements mentioned.

On the right hand side of the chute, a slide-way 43 is provided comprising a base block 90 having on its upper side a central longitudinal dove-tail channel therein parallel to the chute 11, and in this there is reciprocable the carriage block 44. This block has a raised transverse part at its forward end channelled on the upper side at right angles to the chute 95 and receiving slidably a bolt 45 square in cross section carrying at its left end a clearing finger 46 projectable over the slot 16 close below the finger 23, where it extends when the bolt is at the left limit of its movement and in 100 initial position of the block 44. The bolt is retained in the block by a cover plate 47 fastened on the block and having a slot 48 therein over the bolt in which slot there is reciprocable a stud fixed on the bolt and having a 105 roller 49 thereon. The bolt channel in the block opens on both right and left sides of the block and is closed by downturned ends of the cover plate. The bolt is formed at the right hand end with a reduced stem projected 110 slidably through a corresponding aperture in the plate 47 having a helical protractile spring 50 therearound confined between the bolt and plate 47. The bolt is notched at 115 in the side toward the upper end of the slide-way, and a pivoted spring-pressed latch 52 is mounted on the carriage, having a bill portion 53 engaging this notch normally, through a suitable opening in the side of the transverse channelled part of the block 44. This latch 120 has an arm 54 projected toward the right hand side of the carriage over the raised side of the slideway, and movable to release and engage the bolt. The latch and its spring 55 are mounted on a narrowed extension 56 of the carriage which is also of lower height than the transverse channelled part first mentioned. Two vertical guide arms 57 are mounted on the extension perpendicular to the plane of the block. They are formed in 125 130

tegrally as an inverted U-shaped piece having the extremities secured to the face of the extension 56. Between these guides there is engaged a horizontal arm 58 projected transversely over the carriage and spaced from the high side of the slideway, comprising a continuation of a lever 59 formed on the right end of a horizontal shaft 60 mounted rockably below the chute. This shaft is fixed adjustably in a hollow shaft or sleeve 67, which has on its left end a downwardly extending slotted arm 61 in which operates the adjustable wrist pin 62 of a cam-actuated operating arm 63 operated by a suitable cam on the main shaft of the machine, not shown, so that the lever 59 is positively operated in both directions of its movement. At the upper end of the slide, a latch-release strike 64 is secured adjustable longitudinally of the path of the carriage. Its front end is arranged to engage the arm 54 of the latch so as to release the bolt 45 when the finger 46 is aligned immediately below the stop end of the finger 23. The strike comprises a simple plate slotted longitudinally of the slide and held on the raised side of the slide by a screw 65, the lower end of the plate being upturned to engage the arm of the latch.

At the lower end of the slide there is fixed a cam plate 66 having an edge parallel to the major plane of the slide but inclined from the lower part toward the left across the path of the knob 49 of the bolt 45, so that as the carriage passes over the last part of its path through the last part of the downward movement, the knob strikes the plate 66 and is moved to fully retract the bolt before the block reaches the lower limit of its movement. When the bolt is retracted the latch 52 again engages the bolt 45 to hold the bolt retracted until it again reaches the upper position.

In operation, the slot 16 being supplied with nails, with the gate finger 36 closed across the slot, the finger 23 is raised to permit nails to slide by gravity down the slot (any familiar mechanical device for moving stock may be used) until checked by the gate finger 36 after an interval which may comprise a very substantial part of the period for each filling operation of the machine. The finger 23 is then lowered to stop position. During this time the carriage has been at some lower part of its movement after engagement of the cam plate 66, and at, or immediately after the movement when the finger 23 is lowered, the operation of the lever 59 is effected. This operation may be a simple oscillation effected rapidly, the clearing movement being especially intended to be of short duration, so that the charge will be projected from the chute at considerable speed, and if desired, the return movement of the carriage may be much slower. The rapid clearing stroke of the lever 59 occurs

during the movement of the high cam part 28 under the roller 25, and the operation of the lateral cam 41 on the arm 40. The cam 41 engages the arm 40 of the gate and raises the finger 36 just before the clearing finger 46 begins its downward movement. This downward or discharge movement of the finger 46 is completed while the lateral cam 41 is engaged with the arm 40 holding the gate open, and the gate may close immediately after the clearing finger 46 passes therebeyond.

The upper detent may be omitted if the gate operating means is timed to cause closing of the gate promptly after clearing movement of the clearing finger 46, as the clearing finger can enter between nails in the chute without the aid of the upper finger 23. The clearing action is so rapid that an appreciable gap is formed below the stock which advances past the upper detent, affording a sufficient interval for closing of the gate before fresh stock becomes interposed.

The mounting of the lever 59 comprises a horizontal sleeve 67 rockably mounted transversely beneath the chute and receiving the inturned lower extremity or shaft 60 of the lever 59 revolutely therein. A set screw 68 is utilized to secure the shaft 60 to the sleeve. The sleeve is pivoted in a bearing 69, and at the side of the bearing opposite the lever 59 has the depending arm 61 longitudinally slotted. The wrist pin 62 is mounted slidably in this slot and secured adjustably to the arm 61, being also engaged slidably in the upper slotted end of the arm 63 adapted to be operated from the main shaft of the machine to oscillate at the desired intervals. The arm 63 may be mounted and operated by a cam 70 substantially as indicated in Figure 8.

The movement of the clearing pin along the chute may be lengthened by loosening the set screw 68, swinging the lever 59 toward the high end of the chute, tightening the set screw and then adjusting the wrist pin 62 higher in the slot of the arm 61. The reason for the use of the sleeve 67 and set screw 68 will be understood to be the fact that mere adjustment of the wrist pin 62 will lengthen the stroke of the arm 59 so as to cause it to swing too far toward the lower end of the chute, hence the need for adjustment of the arm toward the high end of the chute when the stroke is lengthened. Similarly if the stroke is shortened, it is necessary to use the set screw 68 to adjust the arm toward the lower end of the chute so as to insure complete clearing movement.

I claim:

1. In a counting and discharge device for packaging machines and the like comprising a stock chute, a gate adjacent the delivery end of the chute, means to operate the gate intermittently for opening and closing the

same, a carriage reciprocable parallel to the chute, a clearer thereon projectable to engage stock in the chute and retractable therefrom, means to adjust the gate longitudinally of the chute, means to retract the clearer at the outer limit of movement of the carriage, means including a member adjustable longitudinally of the chute to project the clearer to engage stock in the chute at any predetermined distance from the gate, and means to vary the extent of movement of the carriage.

2. In combination in a counting and discharge device for packaging machines, a stock chute, a carriage reciprocable parallel to the chute, a clearer thereon projectable to engage stock in the chute and retractable therefrom, means to retract the clearer at the outer limit of movement of the carriage, means including a member adjustable longitudinally of the chute to project the clearer, means to vary the extent of movement of the carriage inward from a given outer limit, a gate for stock in the chute comprising a rock shaft beside the chute, a finger secured adjustably thereon for adjustment longitudinally of the chute, an arm on the shaft, means to reciprocate the carriage, and a cam operable to engage the arm to open the gate at the beginning of outward movement of said carriage, and to permit closing of the gate at the termination of outward movement of the carriage.

3. In combination in a counting and discharge device for packaging machines, a stock chute, a carriage reciprocable parallel to the chute, a clearer thereon projectable to engage stock in the chute and retractable therefrom, means to retract the clearer at the outer limit of movement of the carriage, means including a member adjustable longitudinally of the chute to project the clearer, means to vary the extent of movement of the carriage inward from a given outer limit, a gate for stock in the chute, comprising a movable member having a finger thereon movable into and out of the path of stock, said finger being separate from the movable member and secured thereon adjustably for adjustment longitudinally of the chute, and means to move the movable member for operation of the finger within the limits named.

4. A charge clearer for machines of the character described comprising a chute, a guideway parallel to the chute, a carriage reciprocable thereon, a transversely slidable bolt on the carriage, resilient means to project the bolt toward the chute, a latch for the bolt, a release at one limit of movement of the carriage, in the path of movement of the latch to disengage the latch at terminal movement of the carriage, a stud on the bolt the free end of which is exposed beyond the path of the carriage, a cam member fixed at the other limit of movement of the carriage and having a part inclined in the path of

movement of the free end of said stud with the carriage.

5. In a mechanism of the character described, a stock chute, detents spaced longitudinally thereof alternately operable to hold and release stock for longitudinal movement outwardly, a reciprocating clearing device constructed to be protracted across the stock path when at the upper limit of its movement and to be retracted at the lower limit of movement, means adjustable longitudinally of the chute to protract the clearing device, means at the lower end of the chute to retract the clearing device, and means to reciprocate the clearing device.

6. The structure of claim 5 in which the last named means comprises a variable stroke device and means to adjust the stroke thereof.

7. The structure of claim 5 in which the last named means comprises a variable stroke device and means to adjust the stroke thereof, to vary one limit of movement only.

In testimony whereof I affix my signature.

BURPEE D. GREENLAW.
